UNITED STATES PATENT OFFICE.

FRANK E. HAWKINS, OF DEERFIELD, KANSAS, ASSIGNOR OF ONE-HALF TO GEORGE W. BARNES, OF DEERFIELD, KANSAS.

SPARK-PLUG.

1,162,919.

Specification of Letters Patent.

Patented Dec. 7, 1915.

Application filed February 12, 1915. Serial No. 7,828.

To all whom it may concern:

Be it known that I, FRANK E. HAWKINS, a citizen of the United States, residing at Deerfield, in the county of Kearny and State 5 of Kansas, have invented a new and useful Spark-Plug, of which the following is a specification.

The present invention appertains to spark plugs or igniters, and aims to provide a 10 novel and improved device of that character.

One of the objects of the invention is the provision of a spark plug having means whereby a priming charge of gasoline or other fuel may be injected therethrough into 15 the cylinder of the engine, to enable the engine to be started readily.

Another object of the invention is to provide a spark plug of such construction, that it will be self-cleaning, and will therefore 20 not be liable to become fouled or short circuited by the lodging of oil, carbon or other foreign matter upon the electrodes.

A further object of the invention is to provide a spark plug with novel co-operating electrodes.

It is also within the scope of the invention, to construct the spark plug by a unique assemblage of the component parts, whereby the utility of the device is enhanced, and 30 whereby the device is comparatively simple and inexpensive in construction and serviceable, durable, and efficient in use.

With the foregoing and other objects in view which will appear as the description 35 proceeds, the invention resides in the combination and arrangement of parts and in the details of construction hereinafter described and claimed, it being understood that changes in the precise embodiment of the 40 herein disclosed can be made within the scope of what is claimed without departing from the spirit of the invention.

The invention is illustrated in the accompanying drawing, wherein—

Figure 1 is a longitudinal central section 45 of the improved spark plug. Fig. 2 is a lower or inner end view of the spark plug. Fig. 3 is a cross sectional view of the plug taken on the line 3—3 of Fig. 1.

In carrying out the invention, there is 50 provided a metallic body 1 of circular cross section, and having a hexagonal wrench engaging portion 1^a. The body 1 is provided below its upper or outer end with an inwardly projecting annular flange or lip 2,

and the body is further provided with a downwardly or inwardly projecting hollow extension 4 providing a combustion chamber therein. The extension 4 is tapered downwardly or inwardly from the flange or lip 2, and is coaxial with the main portion of the body 1. The internal bore of the extension 4 decreases in diameter from the body 1 to the free end of the extension. The body 1 is externally screw threaded so as 60 to screw within the threaded bore or aperture of an engine cylinder, as usual, and whereby the extension 4 will project into the cylinder. The lower or inner face of the flange or lip 2 is dished or conical, as at 5, 70 whereby the flange or lip 2 decreases in width from its base to its free edge.

A porcelain, mica or similar insulator 6 is carried by the body 1, and embodies an upwardly or outwardly projecting tapered 75 portion 7, and an enlarged base 8 at the basal end of the portion 7. The base 8 seats within the socket 3 of the body 1 and against the flange or lip 2 forming the bottom of the socket, and the base 8 of the insulator is 80 provided with a downwardly or inwardly projecting nipple 9 projecting through the restricted opening 10 formed by the flange or lip 2. The insulator 6 is provided with a central longitudinal bore 11 extending 85 therethrough from end to end, and which receives the central or insulated conductor, as will presently appear.

The central or insulated conductor comprises a metallic tube 12 engaging snugly 90 through the bore 11 of the insulator and having its end portions protruding from the ends of the insulator. A collar 13 is threaded or otherwise secured upon the tube 12 and bears against the lower end of the lower reduced end portion 9 of the insulator and a retaining nut 14 is threaded upon the upper end portion of the tube 12 for clamping the tube to the insulator. A metallic washer 15 is preferably disposed between the nut 14 and upper end of the insulator, and the wire or conductor (not shown) is adapted to be clamped between the washer 15 and nut 14. When the nut 14 is tightened, it will be evident that the insulator 6 will be clamped between the nut 14 and collar 13, to secure the tube 12 to the insulator. The tube 12 serves to provide a longitudinal priming passage or duct 105 through the plug, whereby gasoline or other 110

- priming fuel may be injected into the engine cylinder through the plug. The lower or inner end of the tube 12 extends to and slightly beyond the lower or inner end of the extension 4 of the plug body, and the upper or outer end of the tube 12 is normally closed by means of a screw plug or cap 16, which may be readily removed when it is desired to prime the engine.
- 10 The insulator 6 is secured to the body 1, by means of a packing and retaining nut 17 threaded into the mouth of the socket 3, and bearing against the shoulder of the insulator formed by the base 8. Thus, the base 8 of the insulator will be clamped tightly against the flange or lip 2 of the body. The nut 17 is provided with a tapered bore or aperture 18 surrounding the basal end of the tapered portion 7 of the insulator, and an annular tapered packing 19 is disposed between the walls of the bore or aperture 18 and the walls of the portion 7 of the insulator, whereby when the nut 17 is threaded downwardly or inwardly, it will not only clamp the insulator to the body, but will also compress the packing 19 against the portion 7 for closing the space between the body and insulator. This will prevent leakage, as will be apparent.
- 20 The lower or inner end of the tube 12 carries the central electrode 20, which is enlarged, or which is of greater cross sectional area than the tube 12. The electrode 20 is in the form of a tubular head carried by the lower or inner end of the tube or conductor 12, and is threaded upon the lower end portion of the tube within the lower end or mouth of the extension 4. The upper portion of the electrode 20 is tapered outwardly or upwardly from the plane of the lower or inner end of the extension 4, as at 21, and provides a sharp corner 22 lying in said plane and coöperating with the adjacent sharp edge 23 formed by the free end 45 of the extension 4, to provide an annular spark gap therebetween. The edges or corners 22 and 23 of the electrode 20 and extension 4, respectively, provide the sparking points, it being noted that the lower end 50 of the extension 4 provides the outer electrode which surrounds the inner electrode. It will thus be seen that the electrode or head 20 is provided with the annular sparking edge 22 lying approximately in the plane 55 of the outer annular sparking edge or electrode 23, and that the electrode or head 20 has the tapered portion 21 projecting into the extension 4 and decreasing in diameter from said sparking edge 22.
- 60 The inner electrode 20 is provided with a lower inturned flange or lip 24 seating against the lower end of the tube 12, and providing a restricted outlet aperture 25 through which the priming fuel flows from 65 the tube into the cylinder. The flange or lip of the electrode 20 is provided with a depending or inwardly projecting short nipple 26 surrounding the aperture 25, to cause the priming fuel to drip properly into the cylinder, and to prevent the fuel from flowing around the electrode 20 to the spark gap.
- In use, when the spark plug is secured to the cylinder, it will be evident that by removing the plug or stopper 16, the priming charge of gasoline or other fuel may be injected through the tube 12 into the cylinder, so that the engine may be started readily. After the priming fuel is introduced through the tube 12, the plug 16 is reapplied to the outer end of the tube, for closing the same.
- Attention is directed to the fact, that the tapered extension 4 of the body 1 provides a tapered combustion chamber therein, which is contracted in its mouth, it being noted that the outer electrode is formed by the mouth portion of the extension 4, and that the inner electrode is surrounded by the mouth portion of the extension, so that the annular spark gap between the electrodes 90 provides the entrance or throat for the chamber within the extension. Due to the taper of the extension 4 and the portion 21 of the electrode 20, the annular entrance of the combustion chamber within the extension 4 increases in width from the spark gap upward. When the new charge of fuel enters the cylinder, a portion thereof will flow into the combustion chamber within the extension 4, and when the electrical sparking circuit is closed through the body 1 and tube 12, the spark or sparks jumping across the spark gap, will ignite the fuel for driving the engine, and at the same time, the fuel within the extension 4 will be ignited, 100 and the products of combustion in flowing out through the spark gap from within the extension 4, will blow out any oil, carbon or other foreign matter lodging upon the electrodes. In this manner, the present spark plug or igniter is less liable to be fouled or to become clogged with carbon, and will be self-cleaning, to maintain the efficiency of the plug at all times. This will also prevent the short circuiting of the plug, since 110 no carbon is allowed to remain deposited upon the adjacent or active portions of the electrodes. The electrodes also coöperate in an effective manner, whereby the charge of gaseous fuels within the cylinder will be 115 fired or ignited, notwithstanding the fact that the electrical current is of low amperage.
- Having thus described the invention, what is claimed as new is:—
1. A spark plug comprising a body having a hollow inwardly projecting extension, an insulator mounted within the body, a tubular central conductor extending through the insulator to the end of the extension, the end of the extension forming an outer 120

tubular electrode, and an inner electrode head threaded upon the inner end of the said conductor within and coöperating with the aforesaid electrode, the inner electrode head 5 having an internal annular flange seating against the inner end of the said conductor and forming a restricted outlet aperture for said tubular conductor.

2. A spark plug comprising a body having a hollow inwardly projecting extension, an insulator mounted within the body, a tubular central conductor extending through the insulator to the end of the extension, the end of the extension forming an outer electrode, an inner electrode secured upon the inner end of the said conductor within and coöperating with the aforesaid electrode, the inner electrode having an internal annular flange seating against the inner end of the 15 said conductor, and the said flange having an inwardly projecting nipple.

3. A spark plug comprising a body having an inwardly projecting hollow tapered

extension whose internal diameter decreases from the body to the free end of said extension, the free end of said extension having a sharp edge forming an annular outer electrode, an insulator mounted within the body, a conductor extending through the insulator and having an enlarged head upon 25 its inner end lying within the outer electrode to provide an annular spark gap therebetween, the head forming an inner electrode and having an annular sparking edge lying approximately in the plane of the outer electrode, the head having a tapered portion 30 projecting into said extension and decreasing in diameter from said sparking edge.

In testimony that I claim the foregoing as my own, I have hereto affixed my signature 35 in the presence of two witnesses.

FRANK E. HAWKINS.
